(57) **CLAIM**

The ornamental design for a spray bottle as shown and described.

DESCRIPTION

FIG. 1 is perspective view of a spray bottle showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Broken lines show environmental structure and form no part of our claimed design.

1 Claim, 4 Drawing Sheets
